ENGINE COOLING DEVICE

Walter F. Davis, Nassau County, N. Y., assignor
to Fairchild Aviation Corporation, New York,
N. Y., a corporation of Delaware

Application December 18, 1931, Serial No. 581,851

4 Claims. (Cl. 123—171)

REISSUED

This invention relates in general to air cooling systems for internal combustion engines and more particularly to the construction of baffles therefor.

5 It is an object of the invention to provide a simple and efficient baffle to control the passage of air around the engine cylinders for cooling purposes.

10 It is another object to provide such a baffle which is also easily attached and detached.

15 It is a further object to provide such a baffle which will also cooperate, by reason of its design and place of attachment, with the engine cowling and the cylinder cooling fins to provide a Venturi effect and insure accelerated flow of air and thorough contact thereof with the outer walls of the cylinders.

20 With the foregoing and other objects in view, the invention consists in the combination of parts and in the details of construction herein-after set forth in the following description and appended claims, certain embodiments thereof being illustrated in the accompanying drawing, in which:

25 Figure 1 is a view in side elevation of an inverted internal combustion engine showing the cylinders, their cooling fins and baffles.

Figure 2 is a view in longitudinal cross-section along line 2—2 of Figure 1 taken through the cylinders, the baffles and the engine cowling, showing the cowling on the exhaust side and the baffles on the intake side of the cylinders.

30 Figure 3 is a similar view with the baffles arranged on the exhaust side and the cowling on the intake side of the cylinders.

35 Referring more particularly to the drawing, the particular engine shown in Figure 1 for purposes of illustration is a six cylinder inverted and in line aeronautical engine, the crankcase being indicated at 1, the camshaft housing at 2 and the cylinders extending therebetween. The cylinders are cast separately and arranged in line and are spaced from each other and are provided with suitable cooling fins cast thereon. Figure 1 shows five cooling baffles, one being placed between each cylinder and the cylinder adjacent.

40 Referring to Figure 2, a baffle 5 of light metal having a curved back and inwardly curved ends A and B is placed so as to rest upon the lateral cooling fins 3' and 4' of cylinders 3 and 4 so as to overlap the space therebetween. This baffle is retained in this position by means of a hook 6 attached thereto for engagement by a tension spring 7 which engages a hook 8 on a small piece

9 which may fit between two lateral fins of the cylinders 3 and 4, the fins tending to keep the piece in position and the tension of the spring tending to keep the baffle in position. The arrangement of the other baffles is similar throughout the engine.

45 In the arrangement shown in Figure 2, the baffles are all arranged on the intake side of the engine, the exhaust pipes being shown at 11 adjacent the exhaust ports, the intake ports (not shown) being substantially at the opposite side of the cylinder from the exhaust ports and pipes. It will be appreciated that any suitable type of engine cowling, such as that represented at 10, may be employed to properly di-

50 vert the incoming air in the direction indicated by the arrows. In this instance, the cowling is arranged on the exhaust side opposite the baffles. The incoming air being confined by the cowling is forced against the exhaust side of the cylinder walls and also between the cylinder walls.

55 However, the path of least resistance for the air is to flow in a straight line and therefore it is necessary to provide some induction system for the air in order to insure a free

60 flow of air between the adjacent cylinder walls. This is accomplished by the baffles which, due to their curved backs and inwardly curved ends, produce an air passageway of such a nature be-

65 tween the baffle resting on the lateral cooling fins and the actual cylinder wall that a Venturi effect is obtained. This Venturi effect in causing an accelerated air flow has been found to be an efficient air induction system for insuring the air

70 cooling of the adjacent cylinder walls.

75 The arrangement just described has been found to be so efficient that it may in practice be found desirable to employ the arrangement shown in Figure 3. In this arrangement baffles

80 are arranged on the exhaust side of the space between cylinders 3 and 4 while the cowling 10 is arranged on the intake or other side of the engine over the space between cylinders 3 and 4.

85 Obviously the exhaust side of the cylinder is subjected to the greater degree of heat. How-

90 ever by either of the arrangements shown in Figures 2 and 3, the efficiency of air cooling of the adjacent cylinder walls is obtained. The matter of preference between the two arrange-

95 ments lies only in the question of cooling the exhaust side of the cylinders.

100 The same baffle and Venturi effect may be carried out for the front side of the front cylinder and the rear side of the rear cylinder. A Ven-

105 turi effect is provided for the passage of air

110

115

120

around the front side of the front cylinder and suitable baffle 12 curved, as indicated in Figures 2 and 3, to a part of the engine, such as the front oil drain pipe 14. The rear end of the cowling 13 may also be curved to produce a Venturi effect for the air passing around the rear side of the rear cylinder.

I claim:

1. In an internal combustion engine having spaced cylinders provided with lateral cooling fins, an air cooling baffle detachably secured so as to rest upon said fins and to overlap the space between adjacent cylinders, said plate being curved at both ends and capable of producing a Venturi effect on the air passing between the plate and both of said adjacent cylinder walls, resilient detachable retaining means for said plate extending between said cylinders.

2. In an internal combustion engine having spaced cylinders provided with lateral cooling fins, an air cooling baffle detachably secured so as to rest upon said fins and to overlap the space between adjacent cylinders, said plate being curved and capable of producing a Venturi effect on the air passing between the plate and

the side walls of said adjacent cylinders, retaining means for said plate including a clip adapted to rest between the cooling fins on the opposite side of said cylinders and a tension element between said plate and clip.

3. In an internal combustion engine having spaced cylinders each of which is provided with substantially lateral cooling fins, a cowling for said engine arranged on the exhaust side of said cylinders, baffles arranged between the adjacent cylinder walls and resting on said fins, said baffles having their vertical ends curved inwardly and away from said cylinders, so as to provide an air passageway having the characteristics of a venturi to provide a means of accelerating the airflow between said adjacent cylinder walls.

4. In air-cooled engines, a baffling means bearing on the engine cylinders and extending across the inter-cylinder spaces to direct air to the leeward sides of said cylinders, and a member bearing on the opposite sides of said cylinders, and fastened to said baffling means for clamping the complete assembly in position.
